UNITED STATES PATENT OFFICE

JOHN I. BELLAMY, OF BROOKFIELD, ILLINOIS, ASSIGNOR TO RESERVE HOLDING COMPANY, OF CHICAGO, ILLINOIS, A CORPORATION OF DELAWARE

SELECTOR SWITCH

Application filed July 2, 1928, Serial No. 289,765. Renewed May 26, 1930.

- The present invention relates to new and improved selector switches for use in telephone systems, but is concerned more particularly with switches of the so-called two-wire type in which the slow action of the control relay is obtained by circulating currents in their operating windings rather than in the well-known copper collars or separate short circuited windings.
- 10 This application is for subject matter disclosed in the Bellamy and Stehlik application, Serial No. 167,908, filed February 14, 1927, now Patent No. 1,729,980, Oct. 1, 1929.
- The object of the portion of the invention disclosed in the above mentioned application and covered by this application is the production of new improved circuit arrangements such that change-over relay of a selector may be operated in multiple with the primary operating magnet of the selector and is rendered slow acting by the circulating current which flows between impulses to the magnet owing to the position of the change over relay in the control circuit.
- 25 A further object in the production of suitable circuit arrangements for reoperating the control relay by means of an auxiliary winding so as to guard the selector during release.
- 30 Referring now to the single sheet of drawings, a selector is shown therein containing the usual line, release, change-over, stepping, and switching relay; suitably inter-connected in accordance with the features of this invention.
- 35 Before proceeding with the detailed description of the operation of the improved selector, it may be pointed out that relay A is the line relay; relay B is the release relay; relay C is the change-over relay; relay D is the stepping relay; relay E is the switching relay; V is the vertical magnet; RL is the release magnet; and RO is the rotary magnet.

45 DETAILED DESCRIPTION

Seizure

A detailed description of the operation of the improved selector will now be given.

40 When this selector is seized over conductors 13, 23, and 33, a circuit is closed over the line conductors 13 and 33 in series for line relay A. Relay A operates and closes a circuit for relay C and the vertical magnet V in parallel. It will be noted that a circuit is closed momentarily for the vertical magnet V, while all three springs of the line relay are together, independent of the release relay B, but the duration of this condition is so short that the vertical magnet V does not have time to operate. Relay B operates in series with magnet V, but the vertical magnet V does not operate at this time on account of the relatively high resistance of relay B. Relay C, which is in parallel with the vertical magnet, does not operate for the same reason.

45 At its upper armature, relay B places a ground potential on release-trunk conductor 23 for guarding and holding purposes. At its lower armature, relay B opens a point in the circuit of release magnet RL and closes a locking circuit for itself, thereby preparing an operating circuit for vertical magnet V. At its inner armature, relay B prepares a circuit for rotary magnet RO.

Setting operation

50 Subsequent to the seizure of the selector, a series of interruptions is produced in the circuit of the line relay (usually by a calling device at a calling telephone). Each time its circuit is interrupted, relay A falls back and opens the initial circuit of relay B, at the same time shunting relay B to complete a circuit for the vertical magnet V and change-over relay C in parallel, the circuit including the inner lower contacts of relay E, lower armature, operated, of relay B, and the normally closed contacts of relay A. Vertical magnet V operates each time the circuit is closed and restores each time the circuit is opened. Relay C operates upon the first closure of the circuit, but, being slow acting due to its position in the circuit, does not fall back. Although relay B is short circuited by the line relay contacts each time the line relay falls back, it does not restore due to self-induced circulating current. The slow action of relay C may be explained by pointing out that this relay is in parallel with vertical magnet V.

tical magnet V and that the two are in series with relay B while the line relay is operated, with the result that self-induced current from relay C flows when the shunt is removed from around relay B and joins with the main current from the magnet V. This self-induced current does not attenuate sufficiently to permit the relay to fall back during the vertical movement of the selector, but, when no further impulses are received, at the end of the vertical movement, relay C falls back, as it is adjusted so as not to hold up on the normal current flow. With reference to the induced current from relay C when the shunt removed from ground relay C, it may be pointed out that tests indicate that the induced voltage from relay C is sufficient to send current in the opposite direction through the magnet V, resulting in a quicker falling back of the magnet than when the same circuit is tested with the relay alone.

By the above-mentioned operation of vertical magnet V, the wipers of the switch are raised step-by-step until they come to rest opposite the desired level of bank contacts. When relay C operates it prepares a circuit for stepping relay D which is closed by the off-normal contacts associated with relay D as soon as the switch leaves its normal position. Upon operating, relay D locks itself to the grounded release-trunk conductor 23.

Trunk selection

When relay C falls back shortly after the termination of series of impulses, it opens the initial circuit of relay D, leaving this relay locked to the release-trunk conductor 23, at the same time connecting up the test wiper (the middle one of the three wipers) to the junction of the stepping relay D and switching relay E, and extending ground at its normally closed contacts through contacts of relay B and D to the rotary magnet RO. Magnet RO operates and advances the wipers one step into engagement with the first set of bank contacts in the selected level. Near the end of its stroke, the magnet RO opens the circuit of relay D, whereupon relay D falls back and opens the circuit of the rotary magnet, in addition to opening a further point in its own locking circuit.

If the first trunk line is idle, the rotary operation proceeds no further, and relay E is energized in the manner to be pointed out hereinafter, but, if the first trunk line is busy, the test wiper encounters a ground potential closing a circuit through the inner upper armature, normal, of relay E armature of relay C, the interrupter contacts and associated off-normal contacts for relay D. Relay D reoperates and again locks to the release-trunk conductor, at the same time closing a reoperating circuit for the rotary magnet.

The rotary magnet again operates and advances the wipers another step and again deenergizes the stepping relay.

Trunk seizure

This operation continues until an idle trunk line is reached, which trunk line it may be assumed is the one shown in the drawing, whereupon relay D fails to operate and relay E, which has previously been short circuited now operates from the ground potential on release-trunk conductor 23 and in series with relay C through the interrupter and off-normal contacts. Relay D does not operate in this circuit owing to the relatively high resistance of relay E. Upon operating, relay E removes ground potential from the lower armature of relay B so as to prevent a premature release of the selector, opening the locking circuit of release relay B, leaving this relay energized over the initial circuit through contacts of relay A. At its inner upper armature, relay E opens the test circuit and prepares the holding circuit, connecting the test wiper to the grounded release-trunk conductor 23. At its upper and lower armatures, relay E disconnects conductors 13 and 33 from the windings of line relay A and extends them to the corresponding conductors of the seized trunk through the upper and lower wipers of the switch. Relay A now falls back and short circuits relay B, at the same time opening the initial circuit. Relay B falls back after a slight interval and prepares the release magnet circuit at its lower armature, at the same time removing the local ground potential at its upper armature from the release-trunk conductor 23, an extension of which conductor is previously grounded in the usual manner by the apparatus associated with the seized trunk.

Release

When the ground potential is removed from the release-trunk conductor of the established connection, when the connection is to be broken down, relay E falls back and, among other things, closes a circuit for the release magnet RL at its inner lower armature through the lower armature, normal, of relay D, the lower winding of relay C and the off-normal contacts associated with the release magnet RL. The release magnet operates and relay C reoperates at the same time. Relay C again closes a circuit for relay D, which at this time extends the ground potential applied to its winding by relay C to release-trunk conductor 23, thereby guarding the selector against seizure during release. When the switch is restored to normal by the action of the release magnet RL, the off-normal contacts open whereupon relay C falls back due to the opening of the contacts associated therewith, and the release

magnet RL deenergizes due to the opening of the associated off-normal contacts. Relay C falls back at this time and the switch is ready for use again.

5 In case the feature above-mentioned having to do with guarding during release is not desired, the jumpers 9 may be removed and the terminals 8 in the release circuit may be connected together by a jumper, in 10 which case the release magnet circuit is completed independent of the lower winding of relay C, and relay C does not reoperate upon the release of the selector.

What is claimed is:

15 1. In an automatic switch, a line relay, a release relay, a control relay, contacts on said line relay for closing a circuit when the line relay is operated, said circuit including the release relay and operating magnet in series, self locking contacts on said release relay for closing a locking circuit for maintaining said release relay energized in series with said operating magnet, other contacts on said line relay for shunting said release 20 relay to operate said operating magnet when the line relay falls back, and circuit connections multiplying said control relay with said operating magnet, whereby said control relay operates the first time the magnet is 25 operated and remains operated during successive operations of the operating magnet under the control of the line relay.

2. In an automatic switch, a line relay, a release relay, a control relay, contacts on said line relay for closing a circuit when the line relay is operated, said circuit including the release relay and operating magnet in series, self locking contacts on said release relay, other contacts on said line relay for shunting said release relay to operate said operating magnet when the line relay falls back, circuit connections multiplying said control relay with said operating magnet, whereby said control relay operates the first time the magnet is 30 operated and remains operated during successive operations of the operating magnet, a release magnet for restoring said switch to normal, and another winding on said control relay connected in series with said release magnet so as to cause the reoperation of said control relay during the release of the switch.

3. In a switch control circuit for use in an automatic telephone system, a release relay, an operating magnet, a control relay connected directly in multiple with the operating magnet, and circuit connections for supplying operating current to said release relay through said operating magnet and control relay.

4. In a switch control circuit for use in an automatic telephone system, a release relay, an operating magnet, a control relay connected directly in multiple with the operating magnet, and circuit connections for sup-

plying operating current to said release relay through said operating magnet and change-over relay, said operating magnet and control relay having their windings so proportioned with respect to the release relay that neither of them operates in series with the release relay. 70

5. In a switch control circuit for use in an automatic telephone system, a release relay, an operating magnet, a control relay connected directly in multiple with the operating magnet, circuit connections for supplying operating current to said release relay through said operating magnet and change-over relay, means for transmitting a series of impulses through said operating magnet and change-over relay by intermittently shunting said release relay, the windings of the operating magnet and the change-over relay being so proportioned with respect to one another that the operating magnet falls back at the termination of each impulse when the shunt is removed from around the release relay, while the change-over relay remains operated throughout the series of impulses and falls back at the end of a short interval following the termination of the series. 80

6. In a switch control circuit for use in an automatic telephone system, a release relay, an operating magnet, a control relay connected directly in multiple with the operating magnet, circuit connections for supplying operating current to said release relay through said operating magnet and change-over relay, a release magnet, and a circuit therefor, said release magnet including a second winding on said change-over relay. 95

7. In an automatic switch having primary and secondary operating magnets, a control relay connected in shunt of said primary magnet, impulsive circuits for operating said magnets successively, the winding of said control relay being so proportioned that when the relay operates in parallel with the vertical magnet it remains operated during the entire series of impulses because of self-induced current in its winding, and means including said control relay for closing the impulse circuit for the secondary magnet after the primary magnet has operated. 105

8. In a switch control circuit for use in automatic switching apparatus, a release relay, two switch-operating magnets arranged to be operated successively, a control relay connected in shunt of the first operating magnet, circuit connections for applying operating current to said release relay through the first operating magnet and said control relay, and means including said control relay for operating the second operating magnet only after the first operating magnet has been operated. 120

9. In a switch control circuit for use in automatic switching apparatus, two stepping magnets arranged to respond to two 130

successive impulse series, respectively, a control relay having its winding connected in shunt of the first magnet, a circuit for the first magnet and the relay including a current source but having a resistance element therein which limits the current flow to a value below that required to operate and hold the magnet and relay, the first impulse series being delivered to the first magnet and the relay over a path excluding said resistance element, the relation between the magnet, the relay, and the resistance element being such that the magnet operates on each received impulse and falls back at the end thereof, while the relay operates on the first impulse but does not fall back until the end of the last impulse of the series, and means including contacts on said relay for preventing the delivery of impulses to the second magnet until the relay has operated and has fallen back.

10. In an automatic switching system, an automatic switch having an operating magnet, a release relay, and a control relay; a conductor normally connected to the winding of the release relay, to the winding of the control relay, and to the winding of the magnet; means for operating said release relay by current flow through the winding of the release relay and over said conductor, and means for applying a potential to said conductor to shunt said release relay and to operate said control relay and said magnet.

11. In an automatic switch, a release relay and an operating magnet connected in series, means for temporarily connecting a source of potential to the other side of the release relay to operate the release relay in series with the operating magnet, means for applying said current source to the junction of said release relay and magnet to operate the magnet and shunt the release relay, and a control relay connected in shunt of the operating magnet.

12. In a switching system wherein desired connections are set up by a plurality of automatic switches operated in serial relation responsive to a plurality of impulse series, an operating magnet in one of said switches arranged to respond to the first series of impulses delivered following the taking of the switch for use, a resistance element in said switch arranged to be connected in series with said operating magnet when the switch is taken into use, means for shunting said resistance element to operate said operating magnet each time an impulse is received, and a changeover relay connected in shunt of said operating magnet and in series with said resistance element arranged to effect a changeover operation as soon as said operating magnet has finished operating.

13. In a switching system wherein de-

sired connections are set up by a plurality of automatic switches operated in serial relation responsive to a plurality of impulse series, an operating magnet in one of said switches arranged to respond to the first series of impulses delivered following the taking of the switch for use, a resistance element in said switch arranged to be connected in series with said operating magnet when the switch is taken for use, means for shunting said resistance element to operate said operating magnet each time an impulse is received, a control relay connected in shunt of said operating magnet and in series with said resistance element, and means including said control relay for preventing said operating magnet from responding to the next series of impulses.

14. In a selector, a release relay and an operating magnet normally connected together, a line relay, a front contact on said line relay for closing a circuit through said release relay and magnet, a back contact on said line relay for shunting said release relay, and a control relay connected in shunt of said magnet.

15. In a selector, a line relay, a release relay energized by said line relay, an operating magnet, a control relay, parallel circuits for said magnet and control relay over which said line relay delivers ground impulses on deenergizing, and a circuit including contacts on said release relay for supplying ground potential to the impulsing contacts of said line relay.

16. In a selector, a line relay, a release relay energized by said line relay, an operating magnet, a control relay, parallel circuits for said magnet and control relay to which said line relay delivers ground impulses on deenergizing, a circuit including contacts on said release relay for supplying ground potential to the impulsing contacts of said line relay, a switching relay and means for operating it after the switch has been operated by said operating magnet, and contacts on said switching relay for opening the ground supply connection to the said impulsing contacts of the line relay.

17. In a selector, a release relay and a changeover relay connected in series, primary and secondary operating magnets in said selector, said primary operating magnet being connected in shunt of said control relay, means for shunting said release relay to deliver impulses to said operating magnet and control relay, whereby said operating magnet is intermittently operated and said control relay is operated and maintained operated during the entire time impulses are being delivered to the primary operating magnet, and circuit connections whereby said control relay exercises its controlling function upon falling back at the end of the operation of the primary magnet.

18. In a selector switch having a directed primary movement and a free-hunting secondary movement, primary and secondary operating magnets, a release relay connected in series with said primary operating magnet, and a changeover relay connected in shunt of said primary operating magnet and arranged to cause the selector to change over from its primary movement to its secondary movement at the end of the primary movement.

19. In an automatic switch, a release relay and an operating magnet connected in series, means for shunting said release relay to send current impulses to said operating magnet, a control relay so connected to the magnet and release-relay circuit that it receives current continuously through said release relay and said shunt circuit while impulses are being sent to said magnet, said relay being so adjusted that it operates when the first impulse is delivered to the magnet and remains operated until the last impulse has been delivered, and means whereby said control relay upon falling back upon the termination of the transmission of impulses to the magnet performs an operation necessary to the successful operation of the switch.

20. In a selector, an operating magnet, a release magnet, and a control relay; and means for operating said control relay in parallel with said operating magnet while the selector is being operated, and for operating said control relay in series with said release magnet while the selector is being released.

21. In a selector, primary and secondary operating magnets, a release magnet, a changeover relay arranged to control the secondary operating magnet so that it is not operated until after the primary magnet has been operated, circuit connections for operating said changeover relay in shunt of said primary magnet during the primary operation of the selector, and circuit connections for operating said changeover relay in circuit with said release magnet while the selector is being released.

22. In a selector having an operating magnet and a release magnet, a changeover relay operated in parallel with the operating magnet while the switch is being operated, and means for reoperating the changeover relay while the selector is being released.

23. In a selector having an operating magnet and a control relay connected in parallel circuits whereby the control relay is operated when the operating magnet is operated, and means for subsequently reoperating said control relay without reoperating said magnet.

24. The method of causing the changeover relay of a selector to remain operated between the transmission of successive impulses thereto which consists in maintaining it continuously shunted during an impulse series and

in maintaining a priming current through the relay between impulses of a value insufficient to maintain the relay continuously operated.

25. The method of causing the changeover relay of a selector to remain operated, after it responds to the first impulse of a series, until all impulses of the series have been received, and for permitting it to fall back then, which consists in maintaining the relay continuously shunted during an impulse series, in providing an alternative circuit for the relay between impulses, and in restricting the current flow in the alternative circuit so that the relay will hold up therethrough only momentarily.

In witness whereof, I hereunto subscribe my name.

JOHN I. BELLAMY.

CERTIFICATE OF CORRECTION.

Patent No. 1,787,771.

Granted January 6, 1931, to

JOHN I. BELLAMY.

It is hereby certified that error appears in the printed specification of the above numbered patent requiring correction as follows: Page 3, lines 27 and 42, claims 1 and 2, respectively, for the word "multiplying" read multiplying; and that the said Letters Patent should be read with these corrections therein that the same may conform to the record of the case in the Patent Office.

Signed and sealed this 24th day of February, A. D. 1931.

(Seal)

**M. J. Moore,
Acting Commissioner of Patents.**
